UNITED STATES PATENT OFFICE

SAMUEL MARCUS, OF BROOKLYN, NEW YORK, ASSIGNOR TO MARKON MANUFACTURING CO., INC., OF NEW YORK, N. Y., A CORPORATION OF NEW YORK

TONGUE AND TEETH SET FOR DOLLS AND THE LIKE

Application filed October 4, 1927. Serial No. 223,941.

This invention relates to a tongue and teeth set for dolls and the like, and an object of the invention is to provide a tongue and teeth set adapted to be placed in position by the use of a suitable tool and the set and tool having parts co-operative to effect attachment of the set within the doll head.

A more detailed object is to provide a tongue and teeth set having relatively movable attaching parts bendable into impaled engagement with the doll head to thereby attach the set in position within the head.

A further detailed object is to provide a tongue and teeth set made of sheet metal or other suitable material cut and pressed into appropriate shape providing opposite halves bendable with respect to each other, and to provide attaching tangs on said halves respectively adapted to be driven into attaching relation with the doll head by forced spreading of said halves.

Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawings which are to be taken as a part of this specification, and in which I have shown merely a preferred form of embodiment of the invention:—

Fig. 1 is a vertical sectional view through a portion of a doll head showing the same in position with respect to a tool of the type contemplated herein, a tongue and teeth set being shown upon the tool and in position within the mouth opening of the head.

Fig. 2 is an enlarged vertical sectional view of the tongue and teeth set illustrating the same as carried by the tool and in position preparatory to being attached within the mouth opening of the doll head.

Fig. 3 is a view similar to Fig. 2 but the set being here illustrated as in its fully attached position.

Fig. 4 is a front elevational view of the

tongue and teeth set forming part of this invention, and

Figs. 5 and 6 are views similar to those seen in Figs. 3 and 4 respectively but illustrating a modified form of tongue and teeth set and tool co-operative therewith.

Referring to the drawings for describing in detail the structure therein illustrated the reference character L indicates what may be conveniently herein referred to as the back portion or base of the tongue and teeth set. This base is pressed or otherwise suitably formed to provide a central tongue protuberance or portion as G.

In some instances the tongue portion only may be provided but usually it is desirable to provide also a teeth portion as H. As shown in Figs. 1 to 4 this teeth portion is provided by simply pressing or otherwise forming up a part of the sheet metal on or adjacent to the base at one side of the tongue portion. There may of course be any number of teeth represented, and they may be either above or below the tongue portion, or both.

The tongue portion, as well as the base portion may be colored on its outer surface to correspond with the desired color for the tongue and the interior of the mouth, for instance a red, while the teeth portion H may be colored appropriately to imitate the teeth, for instance white. This coloring may be accomplished either by coloring with paint or otherwise the outer surface of the set after the set has been pressed into shape, or before if preferred as by lithographing in color upon the sheet metal blank from which the set is to be formed.

As hereinabove stated it is a feature of this invention to form the set of two halves bendable with respect to each other and to this end the tongue portion is slit at its opposite sides as at 1—1, the slit extending along the sides of the tongue to a point suitably near the forward end of the tongue so as to permit the base portion L for the respective halves of the tongue to be readily movable away from each other by a simple bending of the material of the tongue portion.

The portion of the base L carried by one half of the tongue is provided with a pair of tangs as 2—2 thereon while the portion of the base which is connected with the remaining half of the tongue carries a pair of tangs as 3—3, the tangs 2—2 being directed away from the tangs 3—3 and all being so disposed that when the tongue is spread the tangs will be driven into the material of the head as clearly indicated by the illustrations Figs. 2 and 3.

It is here noted that a point, approximately as indicated at 4 in Figs. 2 and 3, at or near the apex of the tongue portion G may be considered as a hinge portion about which the tangs 2 and 3 pivot when moved to attaching position and that the tangs 2 and 3 are given a general tangential direction with respect to such point, also that the interior surface portions of the head as at 5 and 6 are disposed in angular relation to the direction of the tangs so that the tangs will readily bite into the material of the head when the halves of the set are spread apart, the tangs thereafter serving as efficient means for permanently retaining the set attached in position within the doll head.

The tool which is designed to co-operate with the tongue and teeth set thus described corresponds in general form to the tool shown and described in an application being filed concurrently herewith, Serial No. 223,940, filed October 4th, 1927. That is to say it includes a support as 7 adapted to be inserted into the doll head through the neck opening of the head and having a tongue-and-teeth-set-carrying member 8 adjustable thereon. Also a pressure lever as 9 arranged above the support 7 and pivotally mounted as at 10 for manually applying pressure against the exterior surface of a doll head when it is desired to force the head downwardly against a tongue and teeth set carried by the carrying member.

In the present instance the carrying member 8 is pivotally mounted as at 11 upon the support 7, being adjustably held in any selected position by means of a set screw 12 engaging within an arcuate slot 13 of a downwardly extending portion 14 of the carrying member.

The carrying member extends above the pivot 11 and its upper end is made of wedge shape as at 14 adapted to engage within the under open side of the tongue portion G of the set, the taper of the wedge being more obtuse than the normal taper of the tongue portion so that when the set is forced downwardly over the wedge the relatively abrupt taper of the carrying member will cause the two halves of the tongue portion to be spread apart for thereby moving the tangs 2—2 and 3—3 into retaining engagement with the doll head.

Obviously, the carrying member may be

driven into the set instead of driving the set onto the carrying member, it being understood that this is optional.

The doll head, indicated generally by the reference numeral 15, may be held by the operator in any position to best locate the tongue and teeth set within the mouth opening of the head preparatory to final attachment of the set within the head. While in some cases the operator may best accomplish this result by simple observation and skill coupled with a proper setting of the set carrying member about its pivot, yet in other instances it is desirable to provide definite guide means and to this end the adjustable rest member as 16 is illustrated as a part of the tool adapted to be engaged by a portion of the doll head for co-operating with the carrying member in definitely locating the position of the head at the time the attaching pressure is applied, it being noted that the rest member 16 is tapered and is longitudinally movable along the support 7 to bring a part of greater or less thickness in position to be engaged by the head.

In operation a tongue and teeth set is first applied upon the wedge portion 14 of the carrying member 8 and the doll head placed over both in approximately the position as indicated in Figs. 1 and 2. Thereupon the head is pressed downwardly against the carrying member, or the carrying member pressed upwardly as preferred, this pressure being applied either directly by the operator's hands or by use of the pressure lever 9 or its equivalent as necessity may dictate, in either case the result being that the wedge 14 will enter relatively into the tongue portion and thereby spread the halves of the set and drive the tangs into attaching position.

The head with the attached set may then be readily lifted away from the tool.

In the modification illustrated in Figs. 5 and 6 the general arrangement is similar to that already described except that in this instance the tongue and teeth set has tangs as 17 and 18 which are themselves bendable into attaching engagement with the doll head without necessity for spreading of opposite halves of the set as in the previous figures. In order to effect proper attachment of this type of set the set-carrying member of the tool, here indicated generally by the reference character 19, includes a separately formed plunger as 20 slidably mounted within a bore as 21 of the carrying member and urged outwardly therefrom by a compression spring 22 arranged within the bore. The outer end portion as 23 of the plunger is shaped to conform to and fit within the hollow interior of the tongue portion as 24 of the set for supporting the set during the time while the doll head is being placed in position thereover, as indicated in Fig. 5, and a guide stop as 25 is provided engaging within a

longitudinal slot 26 provided in the plunger for limiting the outward position of the plunger. The engagement of this stop within the slot 26 is intended also to hold the plunger 5 against any rotary movement with respect to the remainder of the carrying member.

The main body of the carrying member provides an upper surface portion 27 constituting an anvil for engaging or being engaged by the tangs to bend the tangs into attaching engagement with the doll head as 10 indicated in Fig. 6.

In this construction also the set includes one or more parts as 28 and 29 adapted to 15 be brought into engagement against a co-operative part or parts of the doll head, as in Fig. 5, for defining the position of the set with respect to the head prior to the attaching movement of the attaching tangs. 20 At this time the set is supported solely by the movable plunger, and the subsequent movement of the tangs to attaching position by the anvil portion 27 as in Fig. 6, does not disturb the relative positions of the set and 25 head, this being important since it enables an operator to accurately position the set with respect to the mouth opening of the head and to effect attachment of the set without disturbing that position.

30 In operating the structure disclosed in Figs. 5 and 6 a tongue and teeth set is placed upon the portion 23 of the plunger, the plunger being at this time in its elevated position as in Fig. 5. The head is slipped over the set 35 and when the operator has satisfied himself by observation that the head and set are in proper co-related position the necessary pressure is applied, as hereinbefore, to bring the anvil portion against the tangs for driving the tangs into attachment with the head, the plunger meanwhile moving relatively into 40 the bore of the carrying member.

The term "tongue and teeth set" as herein used is merely a commercial term generally 45 used in reference to sets of the type here concerned and is here intended to comprehend any form of device arranged within the mouth or similar opening of a doll head.

As many changes could be made in this 50 construction without departing from the scope of the invention, as defined in the following claims, it is intended that all matter contained in the above description, or shown in the accompanying drawings, shall 55 be interpreted as illustrative only and not in a limiting sense.

Having thus described my invention, what I claim as new and desire to secure by Letters Patent is:—

60 1. A tongue and teeth set for dolls, said set formed from a single piece of bendable material shaped to provide parts movable by bending with respect to each other, and attaching means carried by at least one of said 65 parts adapted to be moved into attaching

position by relative movement of said parts.

2. A tongue and teeth set for dolls, said set formed from a single piece of bendable material shaped to provide parts movable by bending with respect to each other, and an 70 attaching tang formed upon at least one of said parts movable therewith into attaching position.

3. A tongue and teeth set for dolls, said set comprising a base portion and a tongue-like 75 portion, said portions being formed from a single piece of bendable material and being slit to provide opposite parts movable by bending with respect to each other, and the base portion of said parts respectively having attaching tangs thereon movable into attaching position by movement of said parts.

4. As an attachment for doll heads, a tongue member formed of sheet material having its central portion pressed forwardly to 80 represent a tongue, and the portion of said sheet material at the base of the tongue continuing outwardly therefrom and thence forwardly into a general cup shape to represent the interior of a mouth containing the tongue. 85

5. As an attachment for doll heads, a tongue member formed of sheet material having its central portion pressed forwardly to 90 represent a tongue, and the portion of said sheet material at the base of the tongue continuing outwardly therefrom and thence forwardly into a general cup shape to represent the interior of a mouth containing the tongue, together with attaching means formed as an 95 integral part of said sheet material continuing from the margin thereof.

6. A tongue and teeth set for doll heads, said set comprising a base part having a tongue portion projecting forwardly therefrom, said base part and tongue portion being formed from a single integral sheet of metal pressed forwardly at its centre to form the tongue portion, the marginal portion of the piece of metal surrounding the tongue portion and constituting the base part being 100 bent forwardly to form a cup-shaped mouth portion containing the tongue, tangs continuing from the marginal edge of the sheet adapted to be impaled in the material of the head for fixing the set within the head, and 105 means providing teeth in appropriate relation to the tongue.

In testimony whereof I affix my signature.
SAMUEL MARCUS.
